COMBINATION WEATHER STRIP AND
SASH BALANCE

William Edward Bartlett, Atlanta, Ga.

Application October 27, 1950, Serial No. 192,507

10 Claims. (Cl. 20—52.3)

1

This invention relates to a combination weatherstrip and sash balance which can be applied to either old windows or to new.

An object of the invention is to provide an improved weather strip and sash balance which after the initial installation can be applied and removed as desired, thus permitting the ready removal of the sash for the purpose of cleaning the outside thereof, and their replacement without the use of tools.

A further object of the invention is to provide a weather strip and sash balance coextensive in length with the depth of the sash so that the weather is completely excluded.

A further object of the invention is to provide a device of the character indicated which will effectively hold the sash at any elevation as desired.

A further object of the invention is to provide a device of the character indicated which is economical in manufacture, easy to operate and highly efficient for the purposes intended.

Further objects will more particularly appear in the course of the following detailed description.

The invention consists in the novel construction, arrangement and combinations of parts hereinafter more particularly described and claimed.

One sheet of drawings accompanies this specification as part thereof, in which like reference characters indicate like parts throughout.

In the drawing:

Figure 1 is a fragmentary view from the inside of a conventional double sash window frame with sash in position and showing the improved weather strip and sash balance being applied to the lower sash.

Figure 2 is a fragmentary horizontal cross section taken through the window frame and a portion of a sash and the improved strip and sash balance;

Figure 3 is a vertical cross section taken on the line 3—3 of Figure 2;

Figure 4 is a fragmentary back plan view of one end of the improved weather strip and sash balance; and

Figure 5 is a fragmentary perspective view of the hinged connection for the articulated portions of the weather strip and sash balance.

In the modern construction of homes there are numerous objections to the long prevalent form of sash controls comprising cords and weights which have proven objectionable for many years both by the additional space and expense required in the construction of the window frames

2

to provide the necessary wells for the weights, and also in the tendency of the cords to break and the necessity of removing normally permanent parts of the window frame in order to gain access to the weights for the replacement of the cords.

The result of this has been the development of frictional devices and the present invention is directed to an improved frictional slide device which can be interposed between the side edges of the sash and a planar surface of the window frame construction, thereby eliminating entirely the weight well, as well as the sash cords, pulleys, etc., and providing in one device an efficient weather strip and balance for the sash.

Such frictional devices have been heretofore proposed, but in view of the fact that the sash in a normal double sash window are each of a depth in excess of one-half of the total height of the window openings by the width of the central rail, such frictional devices have necessarily been made shorter than the sash, thereby rendering them inefficient to completely exclude wind and weather. If made of the full length of the sash, they could only be installed and removed by removal of the guide strips P on the frame.

In accordance with the present invention the improved weather strip and sash balance is made in articulate form so that it can be bent and thereby permit the insertion of such a weather strip and sash balance of the full length of the sash, notwithstanding the fact that the space available above the sash is less than one-half of the window opening.

The improved weather strip and sash weight of which the attached drawing discloses an efficient embodiment, comprises two frictional slide members 1—1, each of which is preferably beveled on its longitudinal edges as at 2—2 to prevent the entrance and adherence of paint in the normal painting of the window, and each of which frictional strips is preferably formed, as illustrated, of T-cross section having a stem portion 3 adapted to fit in a box-like base member formed of channel cross section having its end portions inturned, as at 5—5, to form such ends. The window sash S are initially formed with longitudinally extending grooves G, and preferably one base section, and its associated slide section, are substantially less in length than the other base section and its associated slide section, to permit the introduction of the combined members with a minimum of flexing. However, the combined lengths of the two associated base sections and slide sections, are equal to the full

length of the groove G and the sash S. Each of the frictional slide members 1—1 is coextensive in length with the respective base members 4—4 and these combined base and slide members, identified by the characters a and b (Figure 5) are hingedly connected by a flat spring strip 7 adapted to lie flat against the web of the channel member forming the base 4 and to be secured by its ends to said web by the rivets 8. These rivets 8 are formed with heads 11 and with their opposite ends 9 of reduced diameter so that when the ends of the rivet are set, as at 10, they will rigidly associate the end of the spring strap 7 with the web of the channel base, as is well illustrated in Figure 3. The heads 11 of the rivets 8 are slidable in countersunk holes 12 set in from the outer face of the slide members 1, and the leg portion 3 of the slide member is normally forced away from the web of the channel base by compression springs 14, a portion of which is seated in the countersunk holes 13 formed in the leg 3 of the slide strip and opening toward the inner face of the web of the channel base.

By reason of the structure thus far described, it will be apparent that the legs 3 of the frictional sections 1 will be slidable in and out of the channel base, being normally forced outwardly by the compression springs 14 with the outward movement limited by the heads 11 of the bolts 8.

At the abutting ends of the friction strips 1—1 are positioned small pieces of felt 25 of substantially the thickness of the inturned end portions 5—5 of the channel base members, so as to provide a complete seal for the two frictional strip members when the same are brought into longitudinal alignment.

At one end of one section of each weather strip and sash balance is provided means for securing the channel base members against longitudinal movement with respect to the sash, comprising plate 20 adapted to bridge the edge of the sash and the adjacent end of the frictional slide, the plate 20 being bent backward upon itself, as at 21, and thence downwardly, as at 22, within the channel base, having its end 23 extending through a slot in the web of the channel base to form an outwardly directed lug 18 projecting beyond the outer face of the web 15. The entire channel member is preferably disposed in a groove G formed in the side edge of the sash and in the base of this groove is driven a nail-like member 16 having a head 17 formed with a transverse notch 18'.

When properly positioned in the groove G of the sash S, lug 18 engages the groove 18' and securely locks the channel base members against longitudinal movement with respect to the sash. From a consideration of Figure 3 it will be apparent that when it is desired to remove the weather strip and sash balance, that pressure against the edge of plate 20 will force the channel member against the pressure of springs 14 toward the frictional slide, thereby permitting the lug 18 to pass out of the slot 18', at which point upward pressure on the underface of the portion 21 will permit the longitudinal withdrawal of the channel base and slide strips from the sash.

In the application of the present invention it will be noted from Figure 1 that by reason of the hinged joint separating the two sections of the base and slide, respectively, one portion of the device can be inserted with the other in an angularly disposed relationship, and thereafter the upper section can be swung into longitudinal alignment with the lower section and the entire

device inserted and withdrawn, as desired, without the removal of any of the covering strips from the window frame.

Where these improved weather strips and sash balances are used in new construction it will be apparent that the structure of the window frames F can be materially simplified and cheapened by eliminating the box structures on each side ordinarily provided to house the sash weights. However, the device can readily be used with frames of conventional structure, thereby eliminating the use of the cords and weights.

While the present specification discloses a highly desirable embodiment of the invention, it will be apparent that other modifications will readily suggest themselves to those skilled in the art, but within the scope of the present invention as claimed.

Having thus fully described my invention, I claim:

1. Weather strip and frictional slide for sash having a groove formed on each side edge, comprising hingedly associated channel members arranged end to end and adapted to seat in said grooves of the sash, frictional slide members, coextensive in length with said hingedly connected channel members, said slide members having portions slidable transversely within the channel members and resilient means interposed between the web of each channel member and its associated slide member operative to normally project the slide outwardly with respect to the channel to frictionally engage the side wall of a window frame.

2. The device of claim 1 with means for removably interlocking the channel members with the sash to prevent longitudinal movement of the channel members within the sash groove.

3. The device of claim 1 in which the hinging connection between the longitudinally aligned channel members comprises a leaf spring positioned within the abutting end portions of the channel members with its ends rigidly secured to the web portions of said channel members, respectively.

4. The device of claim 1 with means associating the channel and slide members formed with stops limiting the transverse sliding movement of the slide members away from the channel members.

5. Weather strip and frictional slide for sash formed with grooves extending lengthwise of their side edges, comprising frame contacting slides for each side of the sash, each of said slides comprising slide sections arranged end to end in longitudinal alignment, base members corresponding in length to the slide sections, said base members arranged end to end in longitudinal alignment, hinge means connecting the abutting ends of said base sections, means for guiding each slide section with respect to its base section to permit sliding movement transversely of said slide and base sections, resilient means operative normally to force each slide section away from its base section, and stop means for limiting said sliding movement.

6. The device of claim 5 with means for removably interlocking one base section of each slide with the sash to prevent longitudinal movement of the base sections within the sash groove.

7. The device of claim 5 with sealing means interposed between the abutting end faces of the slide sections.

8. The device of claim 5 with means adjacent an end of a base section remote from the hinge

connection to engage the base of the sash groove, and a flange on the same end of the base section arranged to overlie the adjacent edge portion of the sash.

9. Weather strip and frictional slide for sash comprising two base members of a combined length equal to the height of the sash with which they are to be used, said members having abutting ends flexibly connected, means for removably associating said base members with the side of a sash and slide members coextensive in length with said base members with means resiliently associating each slide member with a base member to permit a controlled movement of the slide member away from the base member.

10. In combination with a sash having a longitudinal groove on its side edge, a member imbedded in the base of the groove having a head flush with said base and formed with a transverse slot, a combined weather strip and slide comprising a base formed in two sections with hingedly connected abutting ends, slide members corresponding in length with the base sections

5 and resiliently mounted thereon to move transversely thereof, one of the base members having an outwardly directed lug adapted to engage the slot in the head of the imbedded member and a flange adapted to overlie the edge of the sash at the end of the groove.
